US00D890747S

(12) **United States Design Patent** (10) Patent No.: **US D890,747 S**
Lee et al. (45) Date of Patent: ** Jul. 21, 2020

(54) **LAPTOP COMPUTER**

(71) Applicant: **LG ELECTRONICS INC.**, Seoul (KR)

(72) Inventors: **Taejin Lee**, Seoul (KR); **Daihyung Ryu**, Seoul (KR); **Gangho Woo**, Seoul (KR)

(73) Assignee: **LG Electronics Inc.**, Seoul (KR)

(**) Term: **15 Years**

(21) Appl. No.: **35/507,081**

(22) Filed: **Jan. 16, 2019**

(80) **Hague Agreement Data**

Int. Filing Date: **Jan. 16, 2019**

Int. Reg. No.: **DM/201071**

Int. Reg. Date: **Jan. 16, 2019**

Int. Reg. Pub. Date: **Jul. 19, 2019**

(30) **Foreign Application Priority Data**

Jul. 20, 2018 (KR) 30-2018-0033624

(51) LOC (12) Cl. **14-02**

(52) U.S. Cl.

USPC **D14/315**; D14/318

(58) **Field of Classification Search**

USPC D14/203.4, 316, 317, 319-327, 341, 345, D14/346, 501, 502, 507; D21/330

CPC G06F 1/1616; G06F 1/1637; G06F 1/203; G06F 1/1681

See application file for complete search history.

(57) **CLAIM**

The ornamental design for a laptop computer, as shown and described.

DESCRIPTION

1. Laptop computer

1.1 : Perspective View, shown in a closed configuration

1.2 : Front View thereof

1.3 : Back View thereof

1.4 : Left View thereof

1.5 : Right View thereof

1.6 : Top View thereof

1.7 : Bottom View thereof

1.8 : Perspective, shown in an open configuration

1.9 : Front View thereof

1.10 : Back View thereof

1.11 : Left View thereof

1.12 : Right View thereof

1.13 : Top View thereof

1.14 : Bottom View thereof

The broken lines indicate portions of the article that form no part of the claimed design.

1 Claim, 14 Drawing Sheets
